UNITED STATES PATENT OFFICE

2,149,692

LOOM

Philip F. Tirrell, Phillipsburg, N. J.

Application January 26, 1937, Serial No. 122,462

24 Claims. (Cl. 139—232)

My invention relates to improvements in looms for weaving cloth and probably for other purposes.

Briefly stated, the invention has for its primary object to provide means which is readily applicable to standard types of non-automatic looms, without substantial modification of the working parts thereof, for converting same into automatic looms whose working shuttles, the quills of which may carry different varieties of thread, are selectively and automatically changed when their thread is substantially exhausted, the nature of the invention being such that such shuttle changes can be effected without necessitating stopping of the loom.

The invention also contemplates the provision in an automatic loom (or in attachment means for converting a non-automatic loom into an automatic loom) of

(1) A novel magazine for receiving replacement shuttles having different varieties of thread, and which magazine embodies novel means operated by a detector-controlled timing means, or the equivalent, for disposing a particular shuttle in position to be ejected; the magazine further having novel lay-operated means for ejecting the selected shuttle into the shuttle box of the loom;

(2) A shuttle box which in normal running of the loom is controlled by the head motion, or the like, in the usual manner, but which has a novel shuttle-ejecting means in one cell, which latter is automatically brought to alignment with the raceway of the lay to receive an exhausted shuttle; said cell having means for effecting stopping of the loom in the event that the exhausted shuttle is not received for discharge;

(3) A novel empty shuttle receiving container having closure means enabling shuttles to be safely extracted therefrom while the loom is in operation and shuttle changes are being made;

(4) A novel magazine and shuttle box control unit arranged to be set in operation by the feeler motion (or other means, capable of detecting a substantially empty quill in a shuttle) and which control unit preferably acts through the normal shuttle box shifting means, and in conjunction with the head motion, or other control thereof, not only for disposing the shuttle box in position to eject a spent shuttle and receive a new one having the same variety of thread as the ejected one, but also in such subsequent shifts of the shuttle box as are necessary to effect operation of the replacement shuttle from the proper cell of the shuttle box; and

(5) A novel lay-carried actuator for the shuttle ejecting means of the magazine and which is moved to operative position by a shuttle-box-carried member when the shuttle box is shifted to its shuttle-receiving and ejecting position, after the proper shuttle of the magazine has been disposed in position to be ejected therefrom.

Other objects and advantages of the invention reside in certain novel features of construction, combination and arrangement of the various parts, and in modes of operation thereof,—all of which will be readily apparent to those skilled in the art from a reading of the following detailed description of the now preferred example of the invention, which is illustrated in the accompanying drawings forming a part of this specification.

It is to be understood, however, that specific disclosures herein are to be taken merely as illustrative, and that the invention is susceptible of other mechanical expressions within the spirit and scope of the appended claims.

In the drawings, wherein the same reference characters have been used to designate the same parts in all views,

Figure 1 is an elevational view of the head end of a familiar type of non-automatic loom and illustrating the application of my invention thereto, the details of the head motion unit and certain other associated parts having been deleted;

Figure 2 is a front elevational view illustrating the loom as shown in Figure 1;

Figure 3 is a cross-sectional view taken on line 3—3 of Figure 2 through a novel magazine attachment which is carried on a stand that is added as an extension to the head end of the breast beam of the loom, the lay being illustrated in its extreme forward position, and its shifting shuttle box being shown in cross-section immediately below a downwardly acting shuttle-ejecting plunger of the magazine;

Figure 4 is a vertical sectional view taken on the line 4—4 of Figure 2 and showing the shuttle-ejecting means of the magazine in end elevation, certain parts of the lay and shuttle box being broken away and shown in section, as are also certain parts of the shuttle-ejecting means of the magazine;

Figure 5 is a perspective view of the novel magazine detached, certain portions being broken away and sectioned to illustrate the vertically slidable and relatively shiftable shuttle-carrying sections, and also to illustrate the downwardly acting shuttle ejecting plunger;

Figure 6 is a perspective view of a novel shuttle

actuating slide member, which is incorporated in the magazine of Figures 1, 2, 3 and 5;

Figure 7 is a detailed perspective of a swingable shuttle support which is incorporated in the magazine;

Figure 8 is a sectional view taken on the line 8—8 of Figure 2, but illustrating the shuttle box at the uppermost limit of its travel, so that its lower cell is aligned with the raceway of the lay 10 to receive an exhausted shuttle; the view also illustrating the lay-carried dagger actuating the shuttle-ejecting means of the magazine;

Figure 9 is a cross-sectional view taken approximately on the plane of line 9—9 of Figure 2, but illustrating the shuttle-carrying magazine sections of the magazine shifted to a different position from that shown in Figures 1, 2, 3, and 5; and also showing the shuttle actuating slide in the position that it assumes after having actuated a shuttle into the swinging supports (Fig. 7) below the downwardly acting ejecting plunger that is disposed above the open top cell of the shuttle box, which is illustrated fragmentarily in cross-section;

Figure 10 is an end elevational view of the magazine taken approximately on the plane of the line 10—10 of Figure 2, the shiftable shuttle-carrying sections of the magazine being in the same position shown in Figure 8; and a shuttle 30 being illustrated as having been transferred by the depressed downwardly acting plunger into the open top cell of the elevated shuttle box. Certain parts of the magazine are broken away to illustrate the downwardly acting plunger, and the upper part of the shuttle box is shown in cross-section;

Figure 11 is a rear elevational view taken on the plane of line 11—11 of Figure 3, a portion of the rear wall of the magazine being broken away to illustrate the replacement shuttle in the position shown in Figure 9, and to further illustrate the novel swingable shuttle support members of Fig. 7, which support the replacement shuttle prior to the downward movement 45 of the ejecting plunger;

Figure 12 is a top plan view of a shuttle actuating slide of the magazine;

Figure 13 is a cross-section taken on line 13—13 of Fig. 12;

Figure 14 is a fragmentary detail view, partly in section of a portion of the shuttle actuating means of the magazine;

Figure 15 is a perspective view of the swingable bellcrank like plate of Figs. 1 and 2, and 55 showing its supporting bracket and certain sprocket chain guiding idler rolls;

Figure 16 is a detail perspective of the lay-carried magazine operating dagger of Fig. 8;

Figure 17 is a top plan view of the shuttle box, 60 removed;

Figure 18 is a horizontal sectional view through the shuttle box taken on the line 18—18 of Figure 3;

Figure 19 is a horizontal sectional view illustrating the novel bottom cell construction of the shuttle-box, and which cell receives and discharges shuttles whose tread is exhausted;

Figure 20 is a top plan view of a portion of the shuttle box guide and showing a novel shuttle buffer;

Figure 21 is a sectional view taken on the line 21—21 of Fig. 20;

Figure 22 is a cross-sectional view taken on the line 22—22 of Figure 1, and illustrating the clutch-incorporating drive shaft and associated

parts of the novel control unit, which is set in motion by the feeler motion and which governs the action of the shuttle box and shiftable magazine sections for effecting replacement of predetermined shuttles;

Figure 23 is a cross-sectional view taken on the line 23—23 of Figure 22, and illustrating the driven element of the clutch which is incorporated in the control unit;

Figure 24 is a vertical sectional view similar 10 to Figure 22, but showing the clutch members engaged;

Figure 25 is a cross-sectional view through the control unit taken on the line 25—25 of Figure 22, and illustrating a portion of the clutch-holding plate broken away to disclose the cams which operate the shuttle-box and likewise the shiftable shuttle carrying magazine sections, the parts being in the starting position and the clutch disengaged, and a portion of the clutch 20 being broken away to illustrate a wedge actuator and a cam lift for the wedge;

Figure 26 is a perspective view of a wedge member which is shown in Figures 22, 24, and 25, and which is adapted to initially actuate the 25 drive element of the clutch into engagement with the driven element thereof;

Figure 27 is a cross-sectional view taken approximately on the line 27—27 of Figures 1 and 25, the cam shafts, cams and the means operated thereby being illustrated in elevation;

Figure 28 is a fragmentary perspective view of the cam assembly but taken from the side opposite to that shown in Figure 25;

Figure 29 is a wiring diagram illustrating the 35 main feeler motion controlled circuit of the control unit of Figures 1, 14, and 16,—and illustrating the branch circuit which is controlled by the shuttle box lifting means, or the like, for effecting selection for ejection from the magazine of 40 a shuttle having the same character of thread as the shuttle whose quill is substantially exhausted of thread;

Figure 30 is a fragmentary top plan view of the non-shifting shuttle box of the lay and illustrating also the electrical feeler motion and contacts, a portion of the shuttle and shuttle-box being broken away to expose the quill which is substantially full of thread;

Figure 31 is a view similar to Figure 30, but 50 illustrating the thread on the quill substantially exhausted and the contacts of the feeler motion engaging the bare metal collar of the quill whereby to close the circuit of Figure 29 and effect operation of the control unit;

Figures 32—37, inclusive, are diagrammatic views illustrating the successive movements of the shuttle-box with respect to the raceway of the lay when a shuttle corresponding to those in shiftable magazine section 14 and having one 60 variety of thread is being replaced by another having a similar variety of thread; and

Figures 38—43, inclusive, are diagrammatic views illustrating the successive movements of the shuttle-box with respect to the raceway of 65 the lay when a shuttle corresponding to those in shiftable magazine section 13 and having thread of different character from that of the shuttle dealt with in Figures 32—37 is to be replaced.

The non-automatic loom illustrated in Figures 1 and 2 is of a familiar type. Letter A indicates the frame having the head arch A' one end of which provides the head motion receiving seat A2, as shown in Figure 1. A4 indicates the 75

harness which is suspended from the head arch A' by means of the harness mounts A3. Shuttles B, O of usual construction carrying quills B', O', having different kinds of thread, are shown 5 in Figures 3, 30 and 31. The lay C has the race-way C' (Figs. 32-43) and is provided at one end with the non-shifting shuttle box D and at the other end with the shifting shuttle box E, which latter operates in the shuttle box guide 10 F in conventional fashion. The shifting shuttle box E is actuated in the present instance by the conventional shuttle box lifting chain G controlled by the head motion (not shown), and which incorporates the usual rod G' (Fig. 1). 15 In the present instance, the head motion is rigged to actuate shuttle box E in such manner that two picks each will be alternately made by shuttles B, and O. For convenience in description, it will be assumed that the thread of shuttle 20 B is "left twist"; and that the thread of shuttle O is "right twist". This produces a well-known and popular cloth. It is further assumed for convenience that the thread of shuttle B is of blue color and that of the shuttle O is of orange color. 25 The respective shuttles B and O will be referred to hereinafter as "blue" and "orange", respectively.

The shuttle box lifting chain has its upper end connected as usual to a lever of the head motion (not shown) and passes about the idle sprockets 30 H, H' carried by the head motion operated lever H2 (Fig. 2), and by head arch A', respectively. From the idle sprocket H' (Fig. 2) the chain G leads over idle pulley H3 and downwardly and 35 forwardly over the usual but herein novelly mounted, idler K from which it is trained about the usual idler L which is shown in Fig. 1 as mounted on the novel swingable bell-crank like plate 166 to be later described. From idler L chain G passes upwardly and over the idler M which is secured to the bottom of the shuttle 40 box guide F, as shown in Fig. 2. The free end of the chain G is connected to the rod G2 whose lower end has connection with the lateral ear 45 of the usual sleeve N2 slidably mounted on the lifter rod N, and which sleeve effects lifting of the shifting shuttle box E through the spring N' which is coiled about the lifter rod N between the sleeve and the shifting shuttle box E (Fig. 2). 50 This type of loom has the spring Q coiled about the rod Q' extending downwardly from the shuttle box guide F and abutting against a clamp which secures such rod to the rod N whereby if the rod N tends to rise such rise will be resisted 55 by the spring Q.

The rod N has a seat in one of the rocker irons P (Figs. 1 and 2) which carry the picker sticks R which operate the shuttles B, O and have the lug straps R'.

60 The breast piece S of the loom has the removable tray S'. The contacts T2 of an electrical feeler motion T are indicated in Figure 2, as carried by the bracket T' of the frame A at the usual point opposite the non-shifting shuttle box D. The cloth U traverses the conventional roll assembly V.

The loom has the crank shaft W which operates the lay C by means of the connecting rods X, there being the head-motion drive gear Y 70 on the crank shaft, all as shown in Figure 1, which also illustrates the usual bottom shaft Z of the loom.

The foregoing structure is standard except for the mounting 166 of the idlers K and L, as shown 75 in Figures 1, 2 and 15; and except for certain

changes in the shifting shuttle box E, which are best shown in Figures 4, 17 and 19. The novelty in respect to these items will be explained in detail hereinafter.

It is to be understood that the invention is applicable to other types of non-automatic looms for effecting selective and automatic change of shuttles without necessitating the stopping of the loom.

The magazine

10

Figure 3 illustrates the magazine 2 as carried by the stand 4, which is a channel iron bolted to the head end of the breast piece S and providing an extension thereof opposite the shifting 15 shuttle box E. (See also Figs. 2, 4, and 11.)

Bolts 3 carried by angle pieces 5 on top of stand 1 extend through slots 4a in an angle piece 5 on the magazine base plate 6 and in the down-turned end 6a of the base plate to mount magazine 20 2 for vertical adjustment.

The end walls 7 of the magazine casing provide at their forward ends, the downwardly extending legs or extensions 7a which are riveted as at 7b to the downturned end flanges 6a, 6b of 25 base plate 6 adjacent the rear edge thereof, as shown in Fig. 11. The bottom edges of the front and rear walls 8, 9 of the magazine casing are spaced above base plate 6 to admit of passage thereunder of the shuttle actuating slide 10 (see 30 Figs. 3, 9 and 12).

Slide 10 is carried by the block 11 which is slidably carried by horizontal guide bar 12 extending forwardly from base plate 6. The engagement of the undercut walls of bottom groove 11a 35 of block 11 with the bevelled sides of bar 12 hold the bar and block assembled; and cleat 12a (Figs. 3 and 13) keeps block 11 from sliding off the end of bar 12. The operating means for slide 10 will be described later.

Figures 3, 5 and 9 illustrate two laterally spaced shuttle-carrying magazine sections 13, 14, as having their ends slidably carried in vertical grooves 15 in end walls 7 of the magazine casing. Magazine section 13 carries replacement shuttle O 45 having full quills O' of orange thread and which, as heretofore stated, I call "orange shuttles"; and magazine section 14 carries replacement shuttles B having full quills of blue thread. They 50 will be referred to as "blue shuttles". Magazine sections 13, 14, have shuttle-supporting shelves 13a, 14a, respectively, located adjacent each end so as to be clear of the path of shuttle actuating slide 10.

In carrying out the invention, the bottommost shuttles of magazine sections 13, 14, are adapted to be selectively interposed in the path of the actuator slide 10, as indicated in Fig. 3. Rearwardly extending fingers 16 secured on base plate 60 6 are adapted to support the stack of shuttles of whichever magazine section 13, 14 is in lowered position. Such fingers 16 also support the bottom shuttle in its rearward movement under the action of actuator slide 10.

The simultaneous lifting of one magazine section 13, 14, and lowering of the other is accomplished by toggle means at each end of the magazine casing. Each comprises a lever 17 having a medial pivot 17a on end wall 7. Links 18 pivoted 70 to each end of lever 17 are pivotally connected to the respective outwardly extending pintles 13b, 14b of the respective magazine sections. Pintles 14b extend through end wall slots 7c while pintles 13b are offset to ride along the front edges 75

of end walls 7, the front wall 8 being cut away at this point to provide clearance.

Figure 3 illustrates the magazine sections 13, 14 and slide 10 in their normal positions with an orange shuttle O opposite slide 10. As there shown, the section 13 is in lowered position while section 14 is elevated. The reverted lower front- 5 al portion 10a of slide 10 is shown resting upon the cam portion 19a of latch 19, forwardly of its base plate-carried pivot 20 (see Fig. 6). This causes the rear shouldered latch end 19b to be held rocked upwardly above plane of fingers 16 to prevent the lowermost orange shuttle O of magazine section 13 from slipping under the elevated section 14 to thus prevent shift of magazine sections 13, 14 to positions shown in Fig. 9. However, when slide 10 moves rearwardly latch end 19b is positively lowered to the position shown in Fig. 9 by engagement of slide lip 10a 10 with the cam 19c rearwardly of pivot 20.

The magazine sections 13, 14 are shifted from the position shown in Fig. 3 to that of Fig. 9 by the rod 21 which is connected to the forwardly extending apertured ear 13c of magazine section 13 at the upper edge thereof above the forwardly extending flange 8a of front casing wall 8. A cotter pin 21a holds the reduced upper end of rod 21 in the aperture of ear 13c and maintains the subjacent rod shoulder 21b against the under 25 surface of said ear. Front wall 8 and its top flange 8a provide the elongated vertical bearing 22 for rod 21 which extends downwardly through the slots 10b, 12b, 6c of slide 10, guide bar 12 and magazine base plate 6, respectively, and down through hole 1a of magazine stand 1—all as shown in Figure 3.

Substantially, below the magazine stand 1, the rod 21 has a collar 23 secured by a cotter pin 23a, or the like. A coil spring 24 encircling rod 40 21 has its upper end bearing against magazine base plate 6 and its lower end against collar 23 to normally tend to hold the magazine sections 13, 14 in the position shown in Figure 3. Figure 2, considered with Figure 3, also shows a second and heavier coil spring 25 encircling rod 21 between collar 23 and the horizontal apertured flange of the angle piece 26 which is carried by the bell-crank lever 27 (see Fig. 1).

Rod 21 extends through the aperture of the horizontal flange of angle piece 26 and has a cotter pin 28 therebelow to hold the parts assembled. The heavy coil spring 25 is under compression only when the bell-crank 27 is rocked clockwise (Fig. 1) about its pivot 27a which is carried by loom frame A. When bell-crank 27 is rocked clockwise (by means to be later described) coil spring 25, being heavier than spring 24, overcomes the latter and the magazine sections are shifted from the normal position shown in Fig. 3 to that of Fig. 9. By effecting magazine section shift through spring 25 acting on rod 21 through collar 23, breakage of parts will be avoided if something should lodge on base plate 6 or fingers 16 in line with the elevated magazine section 13 60 or 14.

When the shuttle-actuating slide is moved inwardly toward the rear of the magazine 2 (by means to be later described), it delivers to the swingable shuttle supports 29 (see Figs. 3, 4, 5, 70 7 and 11) the bottom-most shuttle of whichever magazine section 13, 14 is in the lowered position. The upper ends of the swingable shuttle supports 29 are pivoted as at 30 transversely of the ends of the rearwardly extending top flange 75 9a of the rear casing wall 9.

Figures 5 and 7 illustrate the swingable shuttle supports 29 as providing block-like lower ends 29a whose opposed inner edges have V-shaped shuttle-end-receiving grooves 29b, which terminate at their rear ends in seats 29c. The seats 29c are located just short of the inwardly extending projections 31 of blocks 29 which serve as stops to limit rearward movement of a shuttle beyond seats 29c. Each swingable shuttle support 29 is actuated inwardly by a coil spring 32 connected thereto at 32a and to the flange 9a, and has the forward end of its block portion 29a provided with an extension lug 29d adapted to engage the outer surface of the adjacent end wall 7 to limit inward swinging movement. Figs. 3, 15 7 and 11 show seats 29c as having cutouts or notches 29e to facilitate release of the shuttle by the head piece 33a of the downwardly acting shuttle-ejecting plunger 33, which is slidably carried in bearing 34 of rear wall flange 9a. Coil spring 35 encircling the upper end of plunger 33 between stop 36 and the upper end of bearing 34 normally holds head piece 33a elevated as shown in Fig. 9. The frontal vertical flange 33b of plunger head piece 33a rides against the outer 20 surface of the rear wall 9.

Actuating means for shuttle-actuating slide 10 and ejecting plunger 33, 33a

The operation of slide 10 and plunger 33 is 30 successively effected by rocking shaft 37 clockwise (Fig. 3) in its bearings 38, 38', which latter are secured as at 38a to the forward under surface of magazine base plate 6 and extend forwardly and downwardly therefrom, as shown. 35

Spring 39, see Fig. 11, which encircles rock shaft 37 has one end bearing against stop collar 40 which compresses the other end against clutch member 41 to urge same against the driven clutch member 42. Pin 40a fixedly secures collar 40 to shaft 37, and clutch element 41 is slidably keyed thereto as at 41a (Fig. 14). Driven clutch element 42 is loose on the shaft 37, which has the pin 43 that serves as a stop to limit movement of clutch elements 41, 42, under ac- 45 tion of spring 39.

The operating lever 44 for shuttle-actuating slide 10 (Fig. 3) has its upper end extending upwardly through guide bar slot 12b into recess 11b of slide block 11 and provided with the roller 50 44b while its lower rectangular end 44a is confined in the end recess 42a of driven clutch element 42 by the action of spring 39 and stop 43, as shown in Fig. 14. It is therefore apparent that a clockwise rock of shaft 37 causes 55 the roller 44b of arm 44 to actuate slide 10 from the position shown in Fig. 3 to that of Fig. 9 to deliver a shuttle B or O to the swingable shuttle supports 29 (Figs. 5 and 7).

A spring actuated pulley 45 (Figs. 2, 3, and 60 14) tends to maintain rock shaft 37 in the Fig. 3 position. Pulley 45 has its hub 45b journaled on the bearing end 46a of fixed member 46 which projects inwardly from rock shaft bearing 38'. Between hub 45b and flange 45a of pulley 45 is 65 a coil spring 48 having one end anchored as at 48a to bracket-carried member 46 and the other end 48b projecting through pulley flange 45a to hold thereto the strap 47 whose opposite end is secured as at 47a to fixed collar 40 of rock 70 shaft 37. The bracket-carried bolt 49 holds washer 49c against the outer end of pulley hub 45b to retain it on bearing 46a, as shown in Fig. 14.

The downwardly acting shuttle-ejecting 75

plunger 33, 33a has the following operative connection with rock shaft 37, reference being had to Figs. 4, 8 and 11. Fulcrum lever 50 is pivoted as at 50a to rear wall 9 of the magazine casing and its bifurcated inner end 50b is pivoted as at 51 to links 52, which in turn are pivoted as at 53 to plunger 33 above head 33a. Links 52 are located in cutouts 33c in opposite sides of the enlarged lower portion of plunger 33; and pivot 51 goes through an enlarged hole 51a in 5 33 so links 52 can rock slightly about pivot 53 (see Fig. 11). The outer end of fulcrum lever 50 extends beyond the plane of inner end wall 1 between rear wall 9 and the shank portion of shuttle support 29 (Figs. 4 and 5) and is pivoted as at 54 to the lower end of the vertical link 15 55 whose upper end has a pivotal connection 56 with the rear end of lever 57 which is fulcrumed as at 57a upon the adjacent end wall 1. The forward end of lever 57 has pivoted (58) thereto the upper end of the long link 59 whose lower end is pivoted (59a) to lever 60 which is loose on rock shaft 37.

The rock shaft-carried end of lever 60, as shown in Figs. 4 and 8, is disposed in the bifurcated portion 61a of the actuating arm 61 fixed to the shaft 37, the arm having a set screw 62 projecting through arm 61 opposite the upper edge of lever 60. When rock shaft 37 has been rocked 25 clockwise (Fig. 3) sufficiently to actuate slide 10 to the position shown in Fig. 9, the set screw 62 engages the adjacent upper edge of lever 60 to depress same. Lever 60, through connections 59, 57, 55, 50, and 52, depresses plunger 33, 33a 30 to eject the hanger carried shuttle into the open top cell 74 of the subjacent shuttle box E. It should here be noted (Fig. 9) that the front ends 16x of the shuttle-supporting fingers intercept and stop the rear edge of block 11 to 35 stop slide 10 and lever 44 in the position shown in Figures 9 and 10. Only a very few degrees of rotational movement of shaft 37 is needed to actuate plunger 33 after set screw 62 engages lever 60, and while this is happening clutch members 41, 42 (Figs. 11, 14) slip slightly due to the fact that slide block 11 is abutting the front ends 40 16x of slide supporting fingers 16x when set screw 62 engages the upper edge of lever 60 to depress same.

The actuation of rock shaft 37 through arm 61 is effected by the forward movement of the lay C when the shifting shuttle box E has been elevated, by means to be hereinafter described, above its uppermost "normal running" position 50 to its spent-shuttle-discharging-and-replacement-shuttle-receiving position shown in Figs. 8, 9 and 10.

Turning to Figs. 4 and 8, the means for actuating rock shaft 37 comprises the adjustable connection 63 having one end pivoted (63a) to shaft arm 61 and its other end pivoted (63b) adjacent one corner of a triangular plate 64, which latter has its opposite corner pivoted (64a) to link 65. The intermediate upper corner of 55 triangular plate 64 is swingably supported by the pivot 66a of a bracket 66 which is secured to the under surface of breast piece S. A pusher arm 67 of angular cross-section is slidably carried in the frame-carried guide 67a and has its forward end pivoted 67c to plate-operating link 65 while its rear end has the notch 67b, to be engaged by the pivoted lay-carried dagger 68 60 when the shuttle box has been raised from normal running position (Fig. 4) to replacement shuttle-receiving position (Fig. 8).

As shown in Fig. 8, dagger 68 is pivoted (68a) to lay C below the shuttle box guide F and adjacent the inner side of same. A lay-carried pin 69 engaging in the bifurcated rear end 68b of dagger 68 sustains same in the position shown in Fig. 4 below the plane of pusher arm 67 until shuttle box E is raised to its elevated replacement shuttle-receiving position shown in Figs. 8, 9 and 10. When this happens, the coil spring 70 on depending shuttle box-carried rod 71 engages the rod-guiding eye 68c of dagger 68 to raise the latter, so that as the lay C comes forward the dagger will engage and actuate forwardly the pusher arm 67 to rock shaft 37 clockwise as viewed in Fig. 3. Coil spring 70 is supported by adjustable stop 70a on rod 71. After rock shaft 37 has been operated by lay dagger 68 to actuate slide 10 and ejector plunger 33, 33a, and lay C has moved rearwardly, the spring actuated means 45, 47 (Figs. 4 and 7) returns 20 rock shaft 37 to the Fig. 3 position.

The shifting shuttle box E

As shown in Figs. 3 and 4, the shifting shuttle box E has four shuttle-receiving cells indicated as 72, 73, 74 and 75. Only the two intermediate cells 72, 73 are used in normal running and carry the shuttles B and O, respectively. Top cell 74 is exclusively used to receive a replacement shuttle and put it in operation, while bottom cell 75 25 is used only to receive and discharge a shuttle whose quill is substantially empty. Each of the top and bottom cells 74, 75 is of special construction. Cells 72, 73 are of standard form and have the usual binders 76 whose outer ends are pivoted on the vertical rod 76a which is carried in the ears E' adjacent the outer end of the front of the shuttle box E, as shown in Figs. 17, 18 and 19. The top shuttle box cell 74 is open at the 30 rear to receive the replacement shuttle from the magazine 2, as indicated in Figs. 3, 9, 10 and its rear wall is provided with a shoulder 74a to overlie the rear top portion of the replacement shuttle. Top cell 74 has a binder 76 similar to those of cells 72, 73. The usual leaf springs 77 35 carried at 77a by shuttle box E hold the free ends of binders 76 inwardly (Figs. 17 and 18) when the respective cells 72, 73, 74 are empty. However, when a shuttle is in any one of said cells 72, 73, 74 it engages the conventional intermediate inbowed portion 76a of the associated binder 76 to urge the free outer end thereof outwardly toward the vertical stop pin 78, which is carried in ears 78a adjacent the inner end of the forward wall of shuttle box E.

The specially designed bottom shuttle box cell 75 has its floor 75b and front wall cut away inwardly of each end to provide the outlet space 75a for the shuttle which is being replaced by the shuttle deposited in top cell 74 from magazine 2. Cooperating deflector members 79, 80 (Figs. 3 and 19) serve to discharge the spent shuttle forwardly and downwardly through outlet space 75a against the buffer member 81 (Figs. 1, 2, 20, 21), which is carried by shuttle box guide F. From buffer 81, the spent shuttle drops into the receptacle 82 (Figs. 1, 2, 3) which is secured as at 82a to stand 1 (Fig. 3). Buffer 81 and spent shuttle container 82 will be described later.

Figure 19 shows that the spent shuttle deflector 79 is disposed forwardly and outwardly across the path of the incoming spent shuttle; and Figs. 3 and 19 disclose the deflector 80 as a forwardly and downwardly inclined shelf. The combined 75

effect of deflectors 79, 80 is, as stated, to direct the shuttle against buffer 81. Deflectors 79, 80 may be fixed in place by welding or otherwise.

The bottom, or spent shuttle discharging cell 75 has a special binder comprising the head piece 83 and the tail piece 84. As shown in Fig. 19, the inner end of the head piece 83 has the pin 83a engaging in the lineal slot 84a in the inner end of the tail piece 84. Since the head and tail pieces 83, 84 are separately pivoted (83b, 84b, respectively) to floor portion 75b, the leaf spring 85 which forces head portion 83 inwardly will, through pin and slot connection 83a, 84a, hold tail piece 84 against the front wall of shuttle box E as shown in Fig. 19 when there is no shuttle in the process of passing through cell 75. Of course, a spent shuttle in transit through cell 75 will actuate tail piece 84 outwardly toward pin 78 through 83, 83a, 84a in the same fashion as the binders 76 of cells 72, 73, 74 when a shuttle is occupying the same. Leaf spring 85 is secured at 85a to the flange 85b of shuttle box E, as shown in Figs. 3 and 19.

Numeral 87 (Fig. 17) designates the protector rod having the fixed arm 86 whose offset vertical finger 86a is disposed opposite the free tail portion of the binder 76 (or 83, 84) of whichever cell 72, 73, 74 or 75 is aligned with the raceway C' of the lay C when same comes forward to the position shown in Fig. 3.

The protector rod 87 normally acts to stop the loom when the lay comes forward to position of Fig. 3; but if there is a shuttle in the cell which is aligned with the raceway C' and with finger 86a, the binder (76 or 84) will project forwardly to engage 86a as lay C comes forwardly. This actuates rod 87 so that the loom will not be stopped.

Reverting to the top shuttle box cell 74, Figs. 4 and 8 show the finger 88 carried by the inner end wall 7 of the magazine 2 and which is adapted, when the shuttle box E is raised to the spent-shuttle-discharging-and-replacement-shuttle-receiving position of Fig. 8, to actuate the illustrated shuttle box-guide-carried means 89, 90, etc., to push the top cell binder 76 far outwardly so that it won't interfere with the deposit of the replacement shuttle in such top cell 74.

This shuttle-box guide-carried and binder-actuating means comprises the forwardly extending dog 89 whose rear end is pivoted as at 89a to the upper end of the fulcrum lever 90, which latter is pivoted (90a) to shuttle box guide F, and has adjacent its lower end the lineal slot 90b. This slot 90b of fulcrum lever 90 receives the intermediately located, laterally projecting pin 91b of the lever 91, whose lower end is likewise pivoted as at 91a to the shuttle box guide F. The upper end of the lever 91 is pivoted (91c) in the bifurcated rear end 92a of the tubular binder pusher member 92, whose forward end receives the threaded extension 92b which may be adjusted inwardly or outwardly to assure proper actuation of the binder 76 of the top cell 74.

Pusher member 92 extends forwardly through a slot F' in the shuttle box guide F, and there is a coil spring 93 on pusher member 92, interposed between the shoulder of its pivot end 92a and the box guide F', to yieldably resist forward movement of such pusher member. A stop pin 94 (Figs. 4 and 8) limits rearward movement of lever 91 under the action of spring 93; and there is a coil spring 95 connected to dog 89 and to a pin 95a of box guide F which normally holds said dog down in contact with the top of the

guide F as shown in Fig. 4. However, when the shuttle box E is raised to the spent shuttle discharging and replacement shuttle receiving position shown in Figs. 8 and 9, an upwardly projecting lug 96 of said box 2 engages dog 89 and lifts it into alignment with the rearwardly extending magazine finger 88 before the lay reaches front center.

Thus, the final forward movement of the lay C to Fig. 8 position at front center results in fulcrum lever 90 being swung rearwardly about its pivot 90a, and the pin and slot connection 90b, 91b between such fulcrum lever 90 and the companion lever 91, which causes the latter to be swung forwardly against the action of spring 93 to actuate the pusher 92 against the binder 76 of top cell 74 to swing it forwardly as shown in Figs. 8 and 9. Figs. 4 and 17 show that there is a special guide and stop element 78a on the upper end of the binder stop pin 78 to admit of this extra, or pusher-induced forward movement of the binder 76 of top cell 74, which uncovers a wide area of such top cell to receive the replacement shuttle from the magazine 2.

The spent shuttle buffer 81 (Figs. 1, 2, 20 and 21)

The buffer 81, heretofore referred to, against which the spent shuttle is discharged by the deflectors 79, 80 of the bottom cell 75 of the shuttle box E is supported by the bracket 97 from the outer end of shuttle guide F. In order to properly position the buffer 81 to intercept the discharged shuttle, two clamp bolt and nut assemblies 98 are extended through one of two laterally spaced arcuate slots 97b in the inner end of bracket 97 and clamped to the top of the rear projection 98a of the shuttle box guide F, as shown in Fig. 20. This enables the bracket 97 and its buffer 81 to be adjusted in a horizontal plane about one or the other of the bolts 98, as 40 an axis.

The buffer 81 comprises the spring metal plate members 99 and 100, and is open at its inner end and at the side adjacent the shuttle box E. As shown in Figs. 20 and 21, plate 99 provides the vertical outer end wall portion 99a whose upper end is bent over the rectangular block member 101, thence inwardly and downwardly as at 99b, and thence horizontally inwardly as at 99c. The outer end wall portion 99a of the plate 99 provides the substantially vertical rearwardly and inwardly extending deflector portion 99d shown in Figs. 20, 21 below the plane of the bracket 97. Deflector 99d is calculated to direct shuttles toward the outer end wall 99a in case bracket 97 gets a little out of adjustment in one direction. The outer end wall 99a has the rawhide padding 104 on its inner surface.

Buffer plate 100 provides the outer or front wall of buffer 81, and has the outer end portion 100a overlapping the rear wall 99a. The inner end of plate 100 is flared outwardly as at 100b and faced with rawhide 105, or the like, to deflect shuttles toward end wall 99a in case the adjustment of bracket 97 is miscalculated slightly in the direction opposite to that heretofore referred to.

A bolt 102 passed through rectangular block 101, and the vertical outer end flange 97c of bracket 97 secures the buffer to the bracket. 70 Rectangular block 101 may be welded or otherwise secured to plate 99, if desired. Likewise, plates 99, 100 may be welded or otherwise secured to one another, or they may be made integral. It is not necessary, however, that the plates be se- 75

cured to one another, other than by the bolt and block 101. A second bolt 103 extends forwardly from bracket flange portion 97c over the inwardly and downwardly extending portion 99c of the plate 99. This bolt 103, except for the inherent yield of the plate 99, prevents buffer 81 from rocking clockwise about pivot bolt 102. A leaf spring 106 secured as at 107 to the projection 97a of the bracket 97, and having its outer end bearing 10 against the outer surface of the rear wall portion 99a of the buffer tends to prevent the same from rocking counter-clockwise about its pivot bolt 102, as viewed in Fig. 21.

15 *The magazine shift and shuttle change control unit (Figs. 1, 22, 23, 24, 25, 26, 27, 28, 29, 30)*

The control unit, which is generally designated at 108 in Figure 1, has two functions. One function is to rock bell-crank 27 (Fig. 1) to shift, 20 through rod 21, the magazine sections 13, 14 from the normal—Fig. 3—position to the Fig. 9 position. The other function is to act through the shuttle box actuating chain G (Figs. 1, 2 and 29) and in conjunction with the normal head motion, 25 or equivalent, control of such chain G to effect appropriate shifting of shifting shuttle box E to admit of selective and automatic replacement, from magazine 2, of either of the different thread carrying shuttles B, O that are being operated. 30 This is accomplished without necessitating the stopping of the loom.

The control unit, 108 as herein illustrated, is designed to be set in motion by the closing of the circuit (Fig. 29) by engagement of the contacts 35 T2 of feeler motion T (Figs. 29, 31) with the bare metal collar of an empty shuttle quill B' (or O'), as shown in Fig. 31.

As will be hereinafter more fully explained, a switch G3, is incorporated in the control unit circuit shown in Fig. 29, and controlled by movement of rod G' of chain G to effect shift of the magazine sections 13, 14 from the Fig. 3 position to the Fig. 9 position only when a "blue" shuttle B is running and requires replacement. No shift 45 of magazine sections 13, 14 is necessary when an "orange" shuttle 13 is running and requires replacement, as the normal Fig. 3 position of the magazine sections disposes the lower orange shuttle O in line with slide 10.

50 Coming now to the detailed description of the control unit 108, the same has a casing supported by the bracket 109 at the rear part of the head end of the loom frame A.

The control unit casing is open at its top and 55 bottom and provides the side walls 110, 111, the front wall 112, and the rear wall 113, as shown in Figs. 22, 24 and 25. The control unit 108 has the main shaft 114 which is constantly driven by its sprocket gear 115 through the chain 116 which 60 is trained thereabout, and about the sprocket gear 117 on bottom shaft Z of the loom; the ratio of 117 to 115 being 2 to 1. The bottom shaft Z is driven from the loom crank shaft W, as usual, turning once every two beats of the lay in the 65 known type of loom to which this invention is applied.

Main shaft 114 is journalled in bearings 118a, 120a provided by plate members 118, 120, which are secured as at 119, 121, respectively, to side walls 111, 110, respectively. It is noted (Figs. 70 22, 24) that bearing portions 118a and 120a, and likewise the subjacent bearing portions 118b and 120b for a driven shaft 126, are seated in holes in said side walls 111, 110.

75 The portion of main shaft 114 between bear-

ing plates 118, 120 is preferably diametrically increased in size by the addition of the close fitting sleeve 122 which is made fast thereto by transverse pins 123. Sleeve 122 has the circumferential shoulder 122a spaced inwardly from bearing plate 118. This shaft formation 114, 122, 122a is the equivalent of an integral structure and may be so made.

A pinion gear 124 is secured to the fixed sleeve 122 of shaft 114 by one of the pins 123 (Fig. 22) 10 and has constant mesh with the large gear 125 which is fast by pin 127 on the subjacent shaft 126 whose pintle ends 126a are carried in the bearings 118b, 120b of plates 118, 120. The ratio of gears 125 and 124 is 2 to 1. The inner end of shaft 126 carries the cam 128 secured by pin 129 through hub 128a. As in the case of the main shaft 114, 122, the second-mentioned shaft may comprise a shaft proper 126a having the close fitting sleeve 126 thereon. Such construction facilitates removal of the parts upon removal of pins 127, 129, 123,—and furthermore, enables the casting to be made as an integral casting.

Above the cam 128, and vertically slidable in the guide-way 118c provided by bearing plate 118, 25 is the clutch-actuating wedge slide 130 having the rectangular opening 130b receiving shaft sleeve 122. Wedge slide 130, Fig. 26, is adapted to be actuated to the Fig. 22 position by cam 128, and releasably held in such position by the latch 30 131 which is pivoted (132) thereto, and is engaged by the movable armature-controlled latch 133 when the feeler motion controlled circuit shown in Fig. 29 is open. Spring 131a tends to hold slide latch 131 in position to engage latch 35 133 as shown (Fig. 25).

The armature-controlled latch 133 is supported by the horizontal portion 134a of a bracket 134 which is secured (134b) to rear wall 113 of the casing. Horizontal bracket portion 134a provides 40 the opening 134c through which projects the slide-carried latch 131. Armature-controlled latch 133 is pivoted (135) to a side flange 134d of the horizontal bracket portion 134a radially of the arc of the bottom surface 133a of its upwardly curved nose. This permits armature latch 133 to be rocked counterclockwise (Fig. 25) about pin 135 to release the slide-carried latch 131.

A vertical projection 136 from bracket 134 carries the solenoid magnet 137 whose armature 138 50 has the pivotal connection 139 with the said armature-controlled latch 133. When the solenoid magnet 137 is energized by the closing of the circuit (Fig. 29) through the engagement of the contacts of feeler motion T with the bare 55 metal collar of a substantially empty quill B', O' (Fig. 31), the armature 138 rocks latch 133 counterclockwise about its pivot 135. This disengages slide-carried latch 131 and same and wedge slide 130 are actuated downwardly by the 60 coil spring 140 (Figs. 22, 24) interposed between the medial pin-incorporating seats 131, 142, respectively, of the bracket portion 134a and upper end of wedge slide member 130, as shown in Figs. 22, 24. This downward movement of the slide 65 and latch 130, 131, takes place to actuate a constantly driven clutch element 144 into driving engagement with the loose clutch element 145 as soon as the constantly rotating cam 128 moves from the slide-sustaining position shown in Fig. 70 22, as will be more fully explained hereinafter.

The constantly driven clutch element 144 which is slidably keyed (143) to the fixedly carried sleeve 122 of shaft 114 is normally held separated from the relatively rotatable com- 75

panion clutch element 145 by coil spring 146 about sleeve 122, as shown in Fig. 22. Shoulder 122a of sleeve 122 limits separating movement of clutch element 144, while the outer end of pinion 147 which is also loose on sleeve 122, and keyed (148) to loose clutch element 145, abuts the opposed face of the aforementioned fast pinion 124 to limit outward movement of same and loose clutch element 145. Figs. 22 and 23 indicate the interengaging portions 144a, 145a of the respective clutch members.

Fig. 22 shows the clutch 144, 145 disengaged and the hub portion 144b of clutch member 144 abutting sleeve shoulder 122a, said clutch hub 144b having the axial cam extension 144c overlying the sleeve shoulder 122a. When latches 133, 131 have been disengaged, and the cam 128 has moved from the Fig. 22 position, the wedge slide 130 is actuated downwardly by its spring 140, as heretofore mentioned, and engages the hub end 144b of the constantly rotating clutch element 144. Then the thickened side portions 130a of the upper portion of slide member 130 ride out on the axial cam portion 144c (Fig. 24) to actuate clutch element 144 into driving engagement with clutch element 145, as shown in Fig. 24.

Fig. 25 illustrates that a segment of the periphery of the clutch element 144 is normally engaged in the correspondingly shaped cut-out 151a of a disk 151 on the cam shaft 150 whose gear 149 is in constant driving engagement with the loose pinion 147, the ratio of gear 149 to pinion 147 being 4 to 1. The engagement of the periphery of clutch element 144 in cut-out 151a of cam shaft disk 151 holds cam shaft 150 against movement until clutch 144 has moved to engage clutch 145. Then the cam shaft 150 will be driven from shaft 114, 122, by gears 147, 149 and the outer part of disk 151 will slip behind the outer flange part of clutch element 144 to hold it in engagement with clutch 145 until gap 151a of disk 151 comes around again.

By this time, the cycle of operation of the control unit will be completed, and spring 146 will move the clutch element 144 to the Fig. 22 position to re-engage its outer peripheral portion in disk recess 151a (Fig. 25), it being understood that the clutch-actuating wedge slide 130 will have been raised to the latched, Fig. 22, position by cam 128 almost immediately after the disk 151 assumes control of the clutch 144. Wedge slide 130 is therefore out of the way when the cycle of operation is completed, and the clutch elements 144, 145 are disengaged.

Cam shaft 150 is formed by the inner shaft 150a closely fitting in and keyed to an outer sleeve, as indicated in Fig. 25. This is the same construction described in connection with shafts 114, 122, and 126a (126) and has the same advantage. Bearings 152 (Fig. 27) support the outer ends of the cam shaft 150 and are carried by side walls 110, 111.

A cam structure comprehending preferably integral cams 153, 154 has its hub 155 keyed to the cam shaft 150 as indicated at 156 in Figs. 25 and 27. Rollers 153a, 154a of a rock plate 160 cooperate with the respective cams 153, 154. The detailed formation of cams 153, 154 for effecting the shuttle box shifts disclosed in Figs. 32-37, inclusive, and in Figs. 38-43, inclusive, respectively, will be later described.

The front wall 112 of the casing has its top provided with the opposed upwardly projecting bearing ears 157, between which is pivoted (158)

the carrier block 159 of the forward lower edge of said upstanding rock plate 160.

Reference has heretofore been made to the fact that the idlers L and K for shuttle box-lifting chain G are specially mounted. This special mount is provided by the bracket 161 (Figs. 1, 2 and 15) whose inset upper flange 162 is bolted to loom frame A. Bracket 161 has the outwardly projecting stub shaft 163 upon which is journalled the idler K in its usual position. The lower part of the bracket 161 has another outwardly projecting stub shaft 164 upon which is journalled, outwardly of the idler K, the rear bearing 165 of the bell-crank-like plate 166 whose forward arm carries the stub shaft 170 of the idler L.

The connecting rod 167 has one end pivoted (168) to the inner face of the upper end of rock plate 160, while its forward end is pivoted to the pin 169 which is adjustably carried in the arcuate slot 171 in the upper portion of the bell-crank-like plate 166. When rock plate 160 is swung counter-clockwise (Fig. 1) the corresponding movement of bell-crank-like plate 166 actuates chain G independently of its head motion control, to elevate active shuttle box E, as indicated in Figs. 33 and 34. Connecting rod 167 is preferably made extensible in any preferred manner, as indicated at 167a.

A pusher rod 172 has its rear end pivoted as at 173 to the outer forward surface portion of rock plate 166, and its slotted forward end 172a is slidably carried on the pin 174, intermediate the ends of the downwardly extending arm of the bell-crank 27. Bell-crank 27, as previously explained, is adapted to be rocked clockwise (Fig. 1) to shift the magazine sections 13, 14 from the position shown in Fig. 3 substantially to that of Fig. 9. This movement of bell-crank 27 is effected by engagement of the inner end of pusher rod slot 172a with pin 174 upon the forward rocking of the rock plate 160 under the action of cam 153, as indicated in Fig. 33.

In order that the magazine section 14 containing the blue shuttles B shall be fully lowered and held in the lowered position (Fig. 9) a sufficient length of time for the slide 10 and ejection plunger 33, 33a to act, I provide the lever 187. This lever 187 is pivoted (189) to the lower end of the bell-crank 27 and works through the slot 186 (Fig. 25) in the upper edge of the front wall 112 of the casing, there being a cross pin 186a above the lever to slidably confine it in the slot 186.

The inner end of lever 187 has its inner face 55 provided with the roller 188. When the pusher rod 172 actuates the bell-crank clockwise, as aforesaid, to substantially dispose magazine sections 13, 14 in the Fig. 9 position, the lever 187 is pulled forwardly so that the inclined end of 60 the cleat 190 (see Fig. 25) on the outer surface of the disk 151 will ride under the roller 188, as shown in Figs. 33 and 34 to fully actuate magazine section 14 to, and hold it in its lowered Fig. 9 position. The length of cleat 190 is sufficient 65 to hold magazine sections 13, 14 in the shifted position (Figs. 9, 33, 34) the length of time necessary for the slide 10 and plunger 33, 33a to operate to effect transfer of a blue shuttle B to the top cell 74 of the shuttle box E.

Inasmuch as only the cam 153 throws rock plate 160 forwardly sufficiently to effect operation of the pusher rod 172 to actuate the bell-crank 27 to shift magazine sections 13, 14 for a change of blue shuttles B, the roller 188 will at 75

all other times be disposed radially inwardly of the cleat 190, as shown in Fig. 25. After the rear end of cleat 190 has passed under roller 188, spring 24 returns magazine sections 13, 14 to the Fig. 3 position, and bell-crank 27 to the Fig. 1 position.

The roller 154a of rock plate 160 which engages cam 154, to effect movement of shuttle box E for a change of orange shuttles O, has the 10 carrier bearing 175 secured as at 175b to the inner face of rock plate 160. Bearing 175 provides stub shaft 175a on which roller 154a is journaled.

The other roller 153a of rock plate 160 is the 15 one which engages cam 153, and it is journaled on bearing pin 177 at the lower end of arm 176 which is pivoted (176a) intermediate its ends to the outer surface of rock plate 160.

A latch plate 178 is pivoted (179) to the outer 20 face of rock plate 160, and has a seat 178a in the low edge of its rear end to engage the forward portion of the upper end of roller arm 176 to hold same perpendicular to cam 153 against counterclockwise movement (Fig. 25). Latch plate 178 therefore maintains roller 153a 25 in position to operatively engage with the cam 153, which latter, along with disk 151 and cam 154, are driven clockwise, as indicated by the arrow in Fig. 25.

30 A weak coil spring 184 connected (184a) to roller arm 176 and to rock plate 160 tends to maintain roller arm 176 against stop 184b with its upper end in position to be engaged by latch plate 178, and its roller 153a in engagement with cam 153. Fig. 28 shows cam 153 as having a slight recess 153x which receives roller 153a in its initial position shown in Fig. 25.

35 A leaf spring 185 (Figs. 1, 25) which is secured (185a) to front wall 112 has its upper end engaging the front edge of rock plate 160 to resist forward rocking thereof under the action of the cams 153, 154 whereby to maintain rollers 153a, 154a in operative engagement with their respective cams.

40 A solenoid magnet 183 secured (183a) to rock plate 160 and having its armature 182 adjustably connected (180b, 180, 180a) to pin 181 of latch plate 178 serves, when energized by the closing of the main and branch circuits of Fig. 29 at points T2, G3, to elevate latch plate 178 45 out of latching engagement with the upper end of roller arm 176. This places rocker plate 160 under the control of cam 154 and roller 154a for making change of the orange shuttle O which is in active running in the loom, and whose quill O' is substantially exhausted of thread, so that it bridges contacts T2 (Fig. 29). As heretofore mentioned, the rod G', which is incorporated in the head motion-controlled shuttle box-lifting 50 chain G, maintains the switch G3 closed when the orange shuttle O is in operation, but is moved to open position when the blue shuttle B is in operation.

55 As shown in Fig. 29, the switch G3 comprises the clamp 191 on rod G' having the pivotal connection 191a with the switch arm 192 which is pivoted (193) to frame A and is adapted to move to bridge the contacts 194.

70 *The feeler motion-controlled main and branch circuits (Fig. 29)*

The transformer 195, or other suitable source of current supply, has one side grounded (196) while a line 197 connects the other side to one terminal of latch-slide releasing solenoid mag-

net 137. A line 198 connects the other terminal of magnet 137 to one feeler motion contact T2, and another wire 199, connected to the other feeler motion contact T2 is grounded as at 200 to complete the circuit having a gap between 5 feeler motion contacts T2.

The magnet 183 for lifting the roller arm retaining latch plate 178 is located in the branch line 201 which also includes the head motion rod-controlled switch G3,—and which line 201 is 10 connected as at 201a in main circuit.

The empty shuttle-receiving receptacle (Figs. 1, 2, 3)

The empty shuttle-receiving container 82, heretofore mentioned, is secured as at 82a to the stand 1 (Fig. 3) and has the front opening 203 which is kept normally closed by the inwardly opening closure 204 which is swung as at 205 from above the opening 203. By thus mounting 20 the closure 204, it is sustained against outward movement by the front wall of the receptacle 82, but may be pushed inwardly with the hand when it is desired to remove spent shuttles from said container. It is noted that the closure extends 25 substantially to the bottom of the receptacle 82. Thus, the hand will be protected against being hit by an incoming spent shuttle from buffer 81.

The operation

30 The operation of the herein described loom equipped with my invention may be summarized as follows:

In the normal operation of the loom, assuming the shuttle box cell 72 of the blue shuttle B is 35 aligned with the raceway C' of lay, the picker stick R actuates shuttle B through the shed to inactive shuttle box D, as lay goes rearward, following which the lay comes forward to beat in the filler. Then harness A3 shifts the shed, and 40 shuttle B makes the second pick which returns shuttle B to cell 72 of box E and lay C beats in filler as before. Just after lay C beats in the second pick of blue thread from shuttle B, and as the lay C starts rearward again, head motion 45 lever H2 (Fig. 2) acts through chain G, G' to raise shuttle box E to align cell 73 containing orange shuttle O with raceway C'. Two picks of orange thread are made by shuttle O, the lay functioning as previously described, following 50 which head motion lever H2 acts through G, G', etc., to lower shuttle box E to again align cell 72 of blue shuttle B with raceway C.

55 First assuming that the quill B' of a blue shuttle B which is in the cell 72 of shuttle box E is substantially out of thread when the lay is at front center prior to a pick, the operation of the mechanism for effecting replacement of same with a full shuttle is as follows:

The parts of the control unit 103 are in the 60 position shown in Figs. 22, 25, 27, 28. The clutch elements 144, 145 of main shaft 114, 122 are disengaged. The main shaft 114, 122 is constantly driven from bottom shaft Z by chain 116, and through gears 124, 125 constantly drives the 65 subjacent shaft 126, 126a whose cam 128 serves to return clutch-actuating slide 130 from the Fig. 24 position to the Fig. 22 position; the cam moving to clear the slide as the lay goes back. The bare portion of the metal collar of the blue 70 shuttle quill B' bridges the contacts T2 of the feeler motion T when the shuttle arrives in box D, closing circuit 195, 197, 131, 198, T2, 199, 200, 196. Magnet 137 being energized releases latch 75 131 of clutch actuating slide 130. Since switch

G3 is open when the blue shuttle B is running, the branch circuit through magnet 183 will not be energized, and latch plate 178 will hold arm 176 in the position shown (Fig. 25) with its roller 153a engaging cam 153. In this connection, it should be remembered that the other cam 154 has no point which is higher than the opposite point of cam 153, except at the side of the starting point recess 153x of cam 153, such recess 153x being disposed to facilitate initial movement of arm 176 and roller 153a under action of spring 184. Nor does cam 154 have any point as high as the high point a of cam 153. Therefore, during replacement of a blue shuttle B rock plate 160 will be entirely under control of cam 153 and roller 153a.

The latch 131 having been released, the clutch-actuating slide 130, urged down by spring 140, is free to engage the hub 144b of the constantly 20 driven clutch 144 when the cam 128 and axial clutch hub cam 144c have moved from the position of Fig. 22. Then axial cam portion 144c of driving clutch 144 rides onto the thickened upper cam portion 130a of slide 130 causing interengagement of clutches 144, 145. This effects drive 25 of cam shaft 150, 150a through gears 147, 149 since the movement of clutch 144 to engage 145 disengages its periphery from the recesses 151a of cam shaft disk 151, shown in Fig. 25. As 30 heretofore explained, the outer part of cam shaft disk 151 rides in behind the flange of clutch 144 to hold it in engagement with clutch 145 during one complete revolution of cam shaft 150, 150a which is the time required for a shuttle change 35 to be effected.

Figure 32 shows the shuttle box cell 72 of the blue shuttle B in running position aligned with raceway C' with lay C moving toward breast piece S to beat in the filler following the pick from cell 40 72, and just before the feeler motion contacts T2 are bridged by bare portion of collar of shuttle quill B' in the box D. After the circuit (Fig. 29) has been closed, the lay C will have travelled about one-fourth of the way toward its rear-most position by the time the clutches 144, 145 45 have been engaged and cam shaft 150, 150a started as above described.

When cam shaft 150, 150a starts, the roller and arm (153a, 176) swing rock plate 160 forwardly. This, through connecting rod 167, rocks bell-crank-like plate 166 counter-clockwise (Fig. 1) depressing idler L which pulls down on chain G to elevate shuttle box E a distance of two cell heights through usual means G2, N, N', etc., but entirely independently of the head motion control H2 of such chain G which has not yet shifted, the loom being on its second pick of blue.

By the time roller 153a is nearly to high point a of cam 153, the rear end of slot 172a in the 60 forward end of pusher rod 172 will have engaged pin 174 of the magazine shift-effecting bell-crank 27. When the roller 153a reaches high point a, magazine sections 13, 14 will have been shifted substantially to the position shown in 65 Figs. 9 and 33, to align the bottom replacement shuttle B with magazine slide 10; and the spent shuttle-discharging bottom cell 75 of shuttle box E will have been aligned with the raceway C' of lay C, as shown in Fig. 33.

70 The modulated shuttle box shift effected by plate 166 is completed by the time the lay has reached its rearmost position and immediately roller 153a reaches high point a the sloping end of cleat 190 engages roller 188 of lever 187 to 75 finish shifting the magazine sections 13, 14 in

the Fig. 9 position. During this time, the substantially exhausted blue shuttle B has, of course, remained in the non-shifting shuttle box D. On the next pick the shuttle B is actuated through the shed and shuttle-discharging cell 5 175 of shifting shuttle box E, which latter discharges it against buffer 81, which drops it into receptacle 82. It should be here pointed out that the lay is moving forward and the buffer 81 extends forwardly of the shuttle box. At this time, 10 the lay is moving forward and is in about the position indicated in Fig. 33, which view shows the spent shuttle B being discharged.

The raising of the shuttle box E, as aforesaid, operates through 71, 70, 70a (Fig. 8) to align the 15 lay-carried dagger 68 with the notched end of pusher arm 67. Thus, when lay C comes forward, the dagger 68 engages pusher arm 67 to push it forwardly, and through 64, 63, 61, 37, 41, 42, 44, 11 to actuate slide 10 rearwardly to dispose the bottom-most blue shuttle B of magazine section 14 in the seats 29c of swingable hangers 29, as indicated in Fig. 9. The final movement of the lay C to front center which places the shuttle box E under shuttle-ejecting 25 plunger 33, 33a causes dagger 67, acting through 64, 63, 61, to rock shaft 37 sufficiently to cause adjustable stop 62 of the fixed shaft-carried arm 61 to engage and depress lever 60 which is loose on shaft 37. This depressing of lever 60 acts 30 through the link and lever assembly 59, 57, 55, 50, 52 to depress shuttle-ejecting plunger 33, 33a, which spreads the swingable supports 29 against the action of springs 32 and drops the replacement shuttle B into the downwardly moving top 35 cell 74 of shuttle box E as is seen in Fig. 34.

It should further be noted that when shuttle box E is raised to the Fig. 8 position, the upstanding lug 96 of the rear wall of top cell 74 elevates dog 89 to align its end with the rearwardly extending finger 88 of magazine 2. Thus, when lay C comes forward and dog 89 engages finger 88, the connections 90, 90a, 90b, 91, 91a, 91b, 91c between dog 89 and pusher 92 causes the latter to engage and throw, well forwardly, the binder 76 of top shuttle box cell 74, so that the former will not interfere with the deposit of the replacement shuttle B in such top cell.

The replacement shuttle B is dropped into the top cell 74 of the shuttle box E just as the roller 153a starts down the remote end of high point a of cam 153 (see Fig. 34) and for this reason, the rear wall of cell 74 is made rather high, and has the L-shaped extension 74x connected to the front wall, as shown in Fig. 2.

It should be remembered that the blue shuttle B having made two picks, and the parts being in the Fig. 34 position, the head motion controlled lever H2, in carrying out its normal operation, will be actuating chain G to elevate the 60 shuttle box E to dispose the orange shuttle-carrying cell 73 to alignment with raceway C' of the lay C. Therefore, in order to offset this movement, (the cell 73 of orange shuttle O now being immediately above raceway C'), it is necessary that the movement of roller 153a from cam portion a to cam portion b, shall, through plate 160 and chain G, have the effect of dropping the shuttle box E instead of lifting it the distance of two cells in order to effect the necessary net drop of the distance of one cell to align orange shuttle cell 73 with raceway C'. This modulated shift is completed by the time the lay reaches front center so that the shuttle O is in the cell aligned with the raceway C'. Fig. 35 shows the shift just 75

described. The length of cam portion *b* of cam 153 is such that the orange shuttle O will have time to make two picks.

Upon completion of the second pick of the 5 orange shuttle O, the head motion lever H2 will, as usual, operate to drop the shuttle box E one cell to align the blue shuttle-receiving cell 72 with raceway C'. However, since the replacement blue shuttle B still reposes in top 10 cell 75, instead of in its usual cell 72, which is next below, this head motion drop must be supplemented by the one cell drop that is effected by movement of roller 153a onto the inwardly disposed cam portion *c*. Fig. 36 shows this last 15 shift, and the length of cam *c* is such as to hold the parts in the Fig. 36 position while the replacement blue shuttle B makes one pick, or, in other words, passes into non-shifting shuttle box D. Immediately this pick is made, the 20 roller 153a passes onto the raised cam part *d* which, through 160, 167, etc., raises shuttle box E to dispose the regular working cell 72 of the blue shuttle in alignment with the lay raceway C' to receive the shuttle B on completion of its 25 second pick as shown in Fig. 37. No head motion actuation of chain G participates in this shift. Thereafter, the disk recess 151a re-engages the periphery of clutch member 144 and the control unit stops.

30 *Replacement of orange shuttle O (Figs. 38-43)*

Since switch G3 is closed when the metal collar of quill O' of an orange shuttle O closes the main circuit, which includes magnet 137 (Fig. 29), 35 the branch circuit line 201 containing magnet 183 will also be closed to effect lifting of latch plate 178. This releases arm 176 so that its roller 153a will simply ride free on cam 153, which puts movement of rock plate 160 under 40 control of roller 154a and its cam 154. The control unit 108 is, of course, put into operation the same as described in connection with replacement of a blue shuttle B.

Figure 38 corresponds to Fig. 32, but shows 45 the orange shuttle cell 73 aligned with raceway C' of lay C just prior to actuation of orange shuttle O through shed to non-shifting shuttle box D. When feeler motion contacts T2 are bridged by the partially bare collar of quill O' (Fig. 31) and cam shaft 150, 150a starts, the roller 154a rides up onto the portion *a'* of cam 154 as shown in Fig. 39, which rocks plate 160 forwardly to raise shuttle box E the distance of one cell. This aligns the bottom or shuttle 50 discharging cell 75 with raceway C' so as to receive the spent orange shuttle O on completion of its second or return pick, as indicated in Fig. 39.

It is noted that portion *a'* of cam 154 is not 55 high enough to effect shift of magazine sections 13, 14 by 172, 21, 21, as previously described, from their normal Fig. 3 position, wherein in the bottom-most orange shuttle O is aligned with slide 10.

60 Figure 40, which corresponds to blue shuttle change Fig. 34, shows the replacement orange shuttle O being deposited in the top cell 74 just as shuttle box E starts to drop to align the blue shuttle cell 72 with the lay raceway C'. This 65 two cell drop of shuttle box E is effected by a one cell drop brought about by the lowering of rock plate 160 due to passage of roller 154a onto cam portion *b'* of cam 154,—plus the normal one cell drop caused by head motion lever H2 through chain G, G2, G', etc., to place blue

75 shuttle cell 72 in line with raceway C' following the second pick of the orange shuttle O. Portion *b'* of cam 154 is of a length sufficient to permit blue shuttle B to make two picks and return to its cell 72. Fig. 41 shows the blue shuttle B in its cell 72 just prior to the making of its first pick.

When blue shuttle B has returned to its cell 72 following its second pick, the shuttle box E is dropped the distance of one cell to align with 10 raceway C', the top cell 74 containing the replacement orange shuttle O. This drop is effected by the movement of roller 154a onto cam portion *c'*. In order to counteract the normal one cell, head motion-induced raise of shuttle 15 box E, incident to the putting of the orange shuttle cell 73 in running position following the second pick of blue shuttle B,—it is necessary that the fall of cam portion *c'* from cam portion *b'* be sufficient to effect a two cell drop of the 20 shuttle box in order to produce the necessary net drop of one cell. Fig. 42 shows completion of this shift just prior to operation of picker stick R to actuate the orange replacement shuttle from top cell 74 through the shed to inactive 25 shuttle box D.

The length of portion *c'* of cam 154 is sufficient to hold the shuttle box E in the Fig. 42 position until the replacement orange shuttle O reaches inactive shuttle box D. By this time, 30 portion *d'* of cam 154 rides under roller 154a and produces a two cell rise of shuttle box E, so that the orange shuttle cell 73 will be aligned with raceway C' to receive the replacement orange shuttle O on completion of its second pick. 35

The operation of slide 10 and shuttle ejecting plungers 33, 33a is the same as described in connection with the replacement of a blue shuttle B; and the same applies, of course, to the operation of top cell binder 76 by the pusher 92 of 40 Figs. 8 and 9.

Particular attention is directed to the fact that Fig. 31 shows that sufficient thread for several more picks is left on the quill B (or O') when feeler motion contacts T2 are bridged. Thus, in 45 the event that the orange shuttle O should require changing while the blue shuttle B is in the midst of the changing operation, or vice versa, enough thread will be left on its quill O' for at least three more picks. It should be noted, 50 in this connection, that if the quill of one shuttle bridges the feeler motion contacts T2 while the other shuttle is going through its replacement cycle, nothing will happen. This is so because the clutch members 144, 145 will already be engaged; 55 and if the quill O' of the orange shuttle O should bridge contacts T2 while a blue shuttle B change is taking place, the release of latch 178 from arm 176 (Fig. 25) will produce no result because at that time the roller 153a of such arm 176 will be 60 on a neutral point *b* of its cam 153 and roller 154a (Fig. 28) will be engaging its cam 154. Since the circuit to the control magnet 183 of latch 178 is closed only momentarily by the quill O' of orange shuttle O, latch 178 will reengage 65 arm 176 before roller 153a reaches the end of the neutral portion of cam 153. As previously mentioned, cam 128 will promptly return clutch actuating slide 130 to the Fig. 25 position.

70 It should be noted that cam 128 (Fig. 25) is always in its "up" position to prevent clutch actuating member 130 from dropping when the shuttles are in the active box E; and is in its "down" position to permit member 130 to drop when the working shuttle is in the inactive box D. 75

Having thus described my invention, I claim:

1. A loom comprising in combination, a frame; lay-carried shuttle box having a spent shuttle discharge cell, a replacement shuttle receiving cell and a plurality of working cells; working shuttles carrying different thread and operating from different predetermined ones of said working cells; means for actuating the working cells to operative position in predetermined sequence in normal operation of the loom; a frame-carried replacement shuttle magazine having a shuttle support and an outlet; replacement shuttles carried by said support and having thread corresponding to the thread of the respective working shuttles; means for shifting said replacement shuttle support to position a predetermined shuttle for movement to said outlet; spent shuttle-operated means for actuating said spent shuttle-receiving and replacement shuttle-receiving cells to operative position; replacement shuttle-selecting means including said working cell actuating means and said spent shuttle-actuated means and operatively connected to said support-shifting means of the magazine; shuttle-ejecting means for said magazine and operable to supply a selected shuttle to said replacement shuttle-receiving cell when the latter is in operative position; lay carried means for operating said shuttle ejecting means, and said spent shuttle-operated means having a portion acting through said shuttle box means to put said replacement shuttle in operative running position from its proper working cell.

2. The combination set forth in claim 1 and including a protection rod-operating binder in said replacement shuttle-receiving cell, a lay-carried pusher member for moving said binder to open position, operating means for said pusher member and including a frame-carried element and a lay-carried element, and means operable to engage one of said elements to align it with the other when the spent shuttle receiving and replacement shuttle-receiving cells move to operative position, whereby to effect operation of said binder pusher member by the lay.

3. The combination set forth in claim 1, and a protection rod-operating binder pivoted adjacent the inlet end of said spent shuttle-receiving cell and terminating short of the opposite end, said spent shuttle-receiving cell having a side outlet adjacent its last-mentioned end, and deflecting means directing a spent shuttle through said outlet.

4. The combination set forth in claim 1, and said spent shuttle-receiving cell having an outlet, and a lay-carried buffer arranged to intercept spent shuttles discharged from said outlet.

5. The combination set forth in claim 1, and a frame-carried spent shuttle-receiving means into which said spent shuttle-receiving cell discharges.

6. In combination with a loom having a lay, a lay race plate, a shifting shuttle box containing a plurality of running shuttles of different thread varieties, and head motion controlled means operatively connected with the box to shift the same to align the different shuttles with the race plate according to pattern; means responsive to substantial exhaustion of a running shuttle and operative to effect an auxiliary shift of the shuttle box during normal operation thereof through any one of a plurality of cycles each individually characteristic to a different variety of shuttle thread, and said means being differently responsive to the different varieties of shuttle thread whereby to shift the shuttle box through the par-

ticular cycle characteristic to the thread variety of the depleted shuttle.

7. In combination with a loom having a lay, a lay race plate, a shifting shuttle box containing running shuttles of different thread varieties, and head motion controlled means in operative connection with the box for operating same to align its different shuttles with the race plate in accordance with pattern; means operable upon substantial exhaustion of a running shuttle and operable to effect an auxiliary shift of the shuttle box through any one of a plurality of cycles each individually characteristic to a different variety of running shuttle thread; and selector means governing the operation of the shuttle box auxiliary shifting means, said selector means being differently responsive to the different varieties of running shuttle thread whereby to cause shifting of the shuttle box through the cycle individually characteristic to the thread variety of the depleted shuttle.

8. In combination with a loom having a lay, a race plate thereon, a shifting shuttle box containing running shuttles of different varieties of thread, and head motion controlled means in operative connection with said box for shifting the same to align its different shuttles with the race plate in accordance with pattern; means operable upon substantial exhaustion of a running shuttle to shift said shuttle box independently of and during its head motion operation through any of a plurality of cycles each individually characteristic to a different variety of thread of the running shuttles; selector means differently responsive to the different varieties of running shuttle thread for determining the character of the independent shifting cycle of the shuttle box; and said selector means governing the operation of the shuttle box shifting means whereby to cause its shifting through the cycle individually characteristic to the thread variety of the depleted running shuttle.

9. In a loom; a shifting shuttle box containing a plurality of running shuttles of different varieties of thread; means for normally operating said box in accordance with pattern; a magazine containing shuttles of different varieties of thread corresponding to the running shuttles; means for effecting an auxiliary shifting of said box relative to the loom lay through any of a plurality of different cycles each individually characteristic to a different variety of thread of the running shuttles; means operable upon substantial exhaustion of a running shuttle to actuate said auxiliary shifting means through the cycle characteristic to the thread of the depleted running shuttle; means for ejecting the depleted shuttle from the box at one point in its auxiliary shifting cycle; and means for transferring a full shuttle of thread corresponding to that of the ejected shuttle from the magazine to the shuttle box.

10. In an automatic shuttle changing loom including a lay, a lay race plate, and a plural cell shifting shuttle box shiftable according to pattern; a plurality of running shuttles in certain of said box cells and having different varieties of thread; another of said box cells comprising an exhausted shuttle receiving and discharge cell; still another of said box cells comprising a replacement shuttle receiving cell; a magazine containing replacement shuttles of thread varieties corresponding to the running shuttles; means operable upon substantial exhaustion of a running shuttle to shift the shuttle box during normal operation to align its exhausted shuttle

receiving cell with the race plate; means operable by shifting of the shuttle box to deliver a replacement shuttle from the magazine to the shuttle box replacement cell, means for transferring the replacement shuttle to the exhausted shuttle cell in the subsequent operation of the shuttle box; magazine carried means for selective presentation of shuttles to the delivery means; and selector means differently responsive to the different varieties of running shuttle thread, said selector means having actuating control of said magazine selective shuttle presenting means, and being operable by the actuation of said shuttle box shifting means whereby to present to the magazine delivery means a replacement shuttle of a thread variety corresponding to that of the depleted running shuttle.

11. Loom shuttle changing mechanism comprising in combination a loom having a lay, a lay race plate, a shifting shuttle box having a plurality of vertically arranged cells wherein the end cells are empty and the intermediate cells contain running shuttles having different varieties of thread, means for elevating said shuttle box with respect to the race plate during a predetermined period of picks and for lowering said shuttle box during a predetermined period of picks whereby to align the running shuttle cells of the box with the race plate in accordance with pattern, a non-shifting shuttle box, a feeler motion in said non-shifting shuttle box, a control unit, an actuator element in said control unit, means operatively connecting said actuator element and the connection between the head motion and the shuttle box for influencing said connection in accordance with movement of said actuator, means in said control unit operable by said feeler motion through different cycles of movement each individually characteristic to a different variety of thread on the running shuttles, means controlled by the position of said shuttle box on actuation of said feeler motion to select the operating cycle for said actuator whereby said actuator is caused to move in the cycle characteristic to the variety of thread on the depleted shuttle in the non-shifting shuttle box, the movement of said actuator through its operating cycle serving to elevate said shuttle box to align its empty bottom cell with the race plate whereby to receive and discharge the depleted shuttle at the end of its return pick, the operating movement of said actuator through its governing connection with the connection between the head motion and the shuttle box serving to modulate the normal operating movement of said connection between the head motion and the shuttle box whereby to align the proper running shuttle cell with the race plate, and magazine means having an operating connection with said actuator whereby to deliver to the upper empty cell of the shuttle box a replacement shuttle of the same variety of thread as that of the depleted shuttle.

12. In a loom having a lay, a lay race plate, a shifting shuttle box containing a plurality of running shuttles of different varieties of thread, a head motion controlled means, a flexible operating connection between said head motion means and the shuttle box for shifting said shuttle box relative to the race plate in accordance with pattern; a magazine containing replacement shuttles of thread varieties corresponding to the running shuttles; a feeler motion for detecting the substantial exhaustion of a running shuttle; magazine carried means for selectively dispensing

a replacement shuttle therefrom dependent upon the position of the shuttle box on actuation of said feeler motion; means for transferring a dispensed replacement shuttle to the shuttle box; means for discharging the exhausted running shuttle from the shuttle box; and means for transferring the replacement shuttle to its proper running shuttle position in the shuttle box, said means including a member movably mounted on the loom frame and adapted for operative engagement with the flexible connection between said head motion and the shuttle box whereby to modulate the action of said flexible connection, and means for positively operating said modulating member, said positive operating means being actuated by operation of the feeler motion.

13. In combination with a loom having a lay, a lay race plate, a shuttle box vertically shiftable relative to the race plate and carrying a plurality of running shuttles having different varieties of thread, a head motion control, an operating connection between said control and shuttle box for shifting same in accordance with pattern, and a feeler motion for detecting the substantial exhaustion of a running shuttle; means for automatically replacing a depleted running shuttle in the shuttle box while the loom is operating comprising a magazine of replacement shuttles of thread varieties corresponding to the running shuttles; means for shifting said shuttle box independently of its operating connection with said head motion; a driven actuator for said independent shifting means and selectively operable in any of a plurality of cycles each individually characteristic to a different variety of running shuttle thread; means operable by actuation of said feeler motion to establish a power drive between the loom mechanism and said driven actuator; means governed by the position of the shuttle box at the actuation of said feeler motion whereby to select the operating cycle for said driven actuator to correspond with the thread variety of the depleted shuttle; and positive operating mechanism between said driven actuator, the shuttle box and said magazine for selectively transferring a replacement shuttle from the magazine to its proper running position in the shuttle box to replace the depleted shuttle, said replacement shuttle being of the same thread variety as that of the depleted shuttle.

14. A magazine for loom shuttles, comprising a shuttle containing casing adapted to be supported on a loom frame and having a shuttle discharge aperture in one wall, a driven pusher member reciprocable through another wall of the casing to dispense a shuttle through the discharge aperture, means carried by said casing externally of and in alignment with the discharge aperture to engage and hold a shuttle when dispensed therethrough, and a plunger carried by said casing in proximity to said shuttle holding means and operable to eject a shuttle held thereby.

15. A magazine for loom shuttles, comprising a shuttle containing casing adapted to be supported on a loom frame, a dispensing slide therein and operable to deliver a shuttle therefrom, means mounted externally on a wall of the casing to receive and hold a shuttle as dispensed, and a shuttle ejecting plunger carried by the casing for movement through said holder means to eject a shuttle when held therein.

16. A magazine for loom shuttles, comprising

- 5 a shuttle containing casing adapted to be supported on a loom frame, dispensing means therein and operable to deliver a shuttle therefrom, a pair of shuttle holding members pivotally mounted on said casing externally thereof and biased to a position to engage and hold the ends of a shuttle as delivered by said dispensing means, a shuttle ejecting plunger carried by and 10 slideable on said casing to engage and press upon a shuttle when in said supporting members, said supporting members having inclined portions movable by a shuttle when pressed by said ejecting plunger whereby to swing said shuttle holding members on their pivots to free the ends of the shuttle as it moves under the action of the ejecting plunger.
- 15 17. The combination with a loom having a lay, a shuttle box shiftable on the lay, and means for shifting the box in accordance with pattern; 20 a replacement shuttle magazine on the loom frame and having a shuttle discharge port in one wall; a dispensing slide operable through the magazine to discharge shuttles through said port; a plurality of shuttle holders in the magazine 25 and movable relative to each other and to the magazine, each said holder supporting a stack of shuttles of the same variety of thread as that of one of the running shuttles; one of said holders being normally positioned to align one of its 30 shuttles with said dispensing slide and discharge port; a driven member movably carried on the loom frame; a positive operating connection between said driven member and the shuttle dispensing slide; normally inactive lay carried 35 means for driving said driven member; shuttle box controlled means for activating said lay carried driving member at a predetermined position of the shuttle box when being shifted; means operable to shift the magazine shuttle 40 holders to select a particular stack for presentation to the dispensing slide; a feeler motion control for said magazine shuttle holder shifting means; and shuttle box controlled means operable to negative said feeler motion control of the magazine shuttle holder shifting means at 45 predetermined shifted positions of the shifting shuttle box.
18. The combination with a loom having a lay, a lay carried shifting shuttle box shiftable thereon, and means for shifting the box in accordance with pattern; of a replacement shuttle magazine; shuttle dispensing means therein; a driven member on the loom frame; a positive operating connection between the shuttle dispensing 50 means and said driven member; normally inactive lay carried means for driving said driven member; shuttle box controlled means for activating said lay carried driven means at a predetermined position of the shuttle box when being shifted; means for transferring a dispensed 55 shuttle to the shuttle box; means for modulating the pattern shifting movement of the shuttle box to bring about the activation of said lay carried driving means; and a feeler motion operatively controlling the actuation of said modulating means.
- 60 19. In combination with a loom having a lay, a non-shifting shuttle box, and pattern controlled means for operating a shifting shuttle box; a plural cell shifting shuttle box having at least two intermediate cells for running shuttles of different thread varieties, the opposite end cells thereof being empty, a connection between said shifting box and the pattern controlled means for normally shifting said box to align its inter- 65

mediate cells with the lay race in accordance with pattern, normally inoperative loom driven means for effecting an auxiliary shifting of said box to align an end cell thereof with the lay race to receive a shuttle picked from the non-shifting box, a feeler motion, and means controlled by the feeler motion to render said auxiliary shift loom driven means operative.

5 20. In combination with a loom having a lay, a non-shifting box provided with a weft detecting feeler, and pattern controlled means for operating a shifting shuttle box; a plural cell shifting shuttle box having at least two cells for running shuttles of different thread varieties, and one cell to receive and discharge a depleted detected shuttle, a connection between said shifting box and the pattern controlled means for normally shifting the box to align its running shuttle cells with the lay race in accordance with pattern, normally inoperative loom driven means for effecting an auxiliary shifting of said box to align its depleted shuttle discharge cell with the lay race, and means controlled by said feeler to render said auxiliary shifting means operative on detected depletion of a shuttle in said non-shifting box.

25 21. In combination with a loom having a lay, a non-shifting shuttle box provided with a weft detecting feeler, and pattern controlled means for operating a shifting shuttle box; a shifting shuttle box having a replacement shuttle cell, at least two cells for running shuttles of different thread varieties, and a spent shuttle discharging cell, a connection between said shifting box and the pattern controlled means for normally shifting the box to align the running shuttle cells with the lay race in accordance with pattern, normally inoperative loom driven means for effecting an auxiliary shifting of said box to align its spent shuttle discharge cell with the lay race, means controlled by said feeler to render said auxiliary shifting means operative on detected depletion of a shuttle in the non-shifting box, and means also controlled by said feeler to replace a spent discharge shuttle by a full shuttle of the same thread variety.

40 22. In combination with a loom having a lay, a non-shifting shuttle box provided with a weft detecting feeler, and pattern controlled means for operating a shifting shuttle box; a shifting shuttle box having a spent shuttle discharge cell, a replacement shuttle cell, and running shuttle cells for shuttles of different thread varieties, a replacement shuttle magazine on the loom frame, a connection between said shifting box and the pattern controlled means for normally shifting the box to align the running shuttle cells with the lay race in accordance with pattern, normally inoperative loom driven means for effecting an auxiliary shifting of said box simultaneously to align its shuttle discharge cell with the lay race and to present its replacement cell to the magazine, means controlled by said feeler to render said auxiliary shifting means operative on detected depletion of a shuttle in the non-shifting box; and means actuated by operation of the auxiliary shifting means to transfer a shuttle from the magazine to the replacement cell of the shifting shuttle box.

45 23. In combination with a loom having a lay, a non-shifting shuttle box provided with a weft detecting feeler, and pattern controlled means for operating a shifting shuttle box; a shifting shuttle box having a spent shuttle discharge cell, a replacement shuttle cell, and running shuttle cells for shuttles of different thread varieties, a

replacement shuttle magazine on the loom frame and containing shuttles of thread varieties corresponding to those of the running shuttles, a connection between said shifting box and the pattern controlled means for normally shifting the box to align the running shuttle cells with the lay race in accordance with pattern, normally inoperative loom driven means for effecting an auxiliary shifting of said box simultaneously to align its shuttle discharge cell with the lay race and to present its replacement cell to the magazine, means controlled by said feeler to render said auxiliary shifting means operative on detected depletion of a shuttle in the non-shifting box, selector means, and means actuated by operation of the auxiliary shifting means to operate said selector means and also to transfer a shuttle from the magazine to the replacement cell of the shifting shuttle box, said selector means being influenced by said pattern controlled means to select in the magazine for transfer a shuttle of the same thread variety as that of the detected depleted shuttle.

24. In a loom having a lay, a non-shifting shuttle box, pattern controlled means for operating a shifting shuttle box, and a replacement shuttle magazine on the loom frame; a shifting shuttle box having a plurality of vertically aligned shut-

tle cells whereof the upper end cell is adapted to receive a replacement shuttle and the lower end cell is adapted to receive and discharge from action a depleted shuttle, a connection between said shifting box and the pattern controlled means for normally shifting said box to align its intermediate cells with the lay race in accordance with pattern, means operable upon depletion of a shuttle arriving in the non-shifting box to effect an auxiliary shifting of said shifting box through a cycle in which at one point the lower end cell is aligned with the lay race to receive and discharge the depleted shuttle when picked from the non-shifting box, and simultaneously the upper end cell is presented to the magazine to box a replacement shuttle therefrom, at another point an intermediate shuttle containing cell is aligned with the race for a predetermined number of picks, at another point the upper end cell is aligned with the race for a pick of the replacement shuttle to the non-shifting box, and at another point completing the cycle the empty intermediate cell from which the deflected shuttle was picked is aligned with the race to box the replacement shuttle when picked from the non-shifting box.

PHILIP F. TIRRELL.
